UNITED STATES PATENT OFFICE

WILHELM B. BRONANDER, OF MONTCLAIR, NEW JERSEY

FIRE EXTINGUISHER

Application filed March 17, 1930. Serial No. 436,281.

This invention relates to fire extinguishers and particularly to an extinguisher and a mounting therefor adapted for use in motor vehicles.

5 As is well known most of the fires which injure and destroy motor vehicles start under the hood or in the carburetor. Furthermore, a vehicle very often takes fire in case of a collision and this fire also originates under the hood.

10 This invention has for its salient object to provide an extinguisher so constructed and so mounted that the extinguisher will automatically operate in case a fire breaks out beneath the hood of a vehicle or in the vicinity of the engine.

15 Another object of the invention is to provide a fire extinguisher so constructed and so mounted that the extinguisher will automatically operate in the event of a collision or a sudden or violent impact of a motor vehicle with another vehicle or other object.

20 Further objects of the invention will appear from the following specification taken 25 in connection with the drawings, which form a part of this application, and in which

Fig. 1 is an elevational view partly in section of an extinguisher constructed and mounted in accordance with the invention; 30 and

Fig. 2 is a detail elevational view taken at right angles to Fig. 1.

The invention briefly described consists of an extinguisher casing, means for clamping the casing beneath the hood of a motor vehicle and a hammer controlled by a fusible element and adapted in case of fire to automatically operate and cause the extinguishing liquid to be liberated. The extinguisher, furthermore, comprises means within the casing positioned for engagement by a frangible extinguisher container in the event of a sudden or violent impact of the vehicle with another vehicle or other object. The container is slidably mounted in the casing and is normally held by a spring in a position spaced from an anvil which is disposed in the end of the extinguisher casing.

50 In the particular embodiment of the invention illustrated there is shown a portion

of a hood of a motor vehicle and a tie rod 10 of the usual construction which connects the radiator to the dash. The fire extinguisher comprises an outer casing 11 having a pair of clamps 12 and 13 which encircle the casing and are secured to the tie rod 10. A frangible container 15 is slidably mounted in the casing 11 but is normally held against endwise movement by a spring 16 which is disposed in one end of the casing and engages a washer 17 which in turn engages the end of the frangible container. The washer is preferably made of felt or other suitable material.

55 The end of the casing in which the spring 16 is mounted has secured therein an anvil 18. The frangible container is shown as tapered at the end 19 thereof, the tapered end being disposed opposite the anvil and normally in spaced relation thereto. The spring 16 is of such strength that it will hold the frangible container against endwise movement and under normal conditions, but in case the vehicle is suddenly or violently stopped by a collision the frangible container 70 will slide longitudinally in the casing and the impact of the end 19 of the container with the anvil 18 will cause the container to break, thus releasing the fire extinguishing liquid therein. The casing 11 is perforated 75 as shown at 20 to permit the escape of the fire extinguishing liquid therefrom when the container is broken.

80 In order to effect the release of the fire extinguishing liquid in case of fire a hammer 25 is carried by an arm 26 actuated by a spring 27. The arm 26 is pivoted on lugs 28 carried by the clamp 12 and the spring tends to swing the arm about its pivot in an anti-clockwise direction. The arm is normally held against actuation of the spring by means of a fusible link 30 of any suitable construction which engages at one end a lug 31 carried by the arm and at its other end a lug 32 formed on or carried by the end of the 85 casing 11.

90 In case a fire breaks out under the hood of a vehicle, the rise in temperature will cause the fusible link to give way thus permitting the arm 26 and the hammer 25 to swing under 95 100

the action of the spring 27. The hammer will thus be actuated into violent contact with the casing 11 and the contact of the hammer with the casing will cause the container to be broken thus releasing the fire extinguishing liquid therefrom.

From the foregoing description it will be evident that a fire extinguisher has been so designed and so mounted that it will operate automatically in case of fire and will furthermore, operate automatically in case of a collision or violent impact of the vehicle with another object thus insuring the extinction of a fire in case a fire should break out on collision.

Although one specific embodiment of the invention has been particularly shown and described, it will be understood that the invention is capable of modification and that changes in the construction and in the arrangement of the various cooperating parts may be made without departing from the spirit or scope of the invention, as expressed in the following claims.

What I claim is:

1. In combination, a supporting element located on a motor vehicle, a fire extinguisher casing extending longitudinally of the vehicle, means for clamping the fire extinguisher casing to said element, a frangible container movably mounted for longitudinal movement in said casing, means for normally holding the container against movement, and means engageable by the container to break the container when the container moves a predetermined extent in the casing, against the action of said holding means.
2. In combination, a supporting element located on a motor vehicle, a fire extinguisher casing, means for clamping the fire extinguisher casing to said element, a frangible container movably mounted in said casing for movement longitudinally of the vehicle, spring means for normally holding the container against movement, and means engageable by the container to break the container when the container moves a predetermined extent in the casing, against the action of said holding means.
3. In combination, a supporting element located on a motor vehicle, a fire extinguisher casing extending longitudinally of the vehicle, means for clamping the fire extinguisher casing to said element, a frangible container movably mounted for longitudinal movement in said casing, means for normally holding the container against movement, and an anvil in the casing engageable by the container to break the container when the container moves a predetermined extent in the casing, against the action of said holding means.

WILHELM B. BRONANDER.
